UNITED STATES PATENT OFFICE

ALEC VERNON WATSON, OF ST. ALBANS, ENGLAND, ASSIGNOR OF ONE-HALF TO
THOMAS ANDERSON DAVIS, OF LONDON, ENGLAND

SAFETY RAZOR

Application filed April 7, 1928, Serial No. 268,243, and in Great Britain April 23, 1927.

This invention of improvements in safety razors is concerned with the adaptation of safety razors for insertion bodily into a stropping device without the necessity for removing the blade or altering the condition 5 of the razor parts.

In the specification filed with the concurrent patent application, Serial Number 268,244 a stropping device is described of the reciprocal carriage type and the improvements to be described in this present 10 specification are particularly intended for the adaptation of a safety razor for insertion bodily into the stropping apparatus of 15 the said concurrent patent application.

One object of the invention is to provide the safety razor with means whereby it may be disposed with accuracy in supports in the carriage so that the edge of the blade will 20 be in proper relation to the strop.

A further object is to provide the blade with a rockable guard adapted for being rocked automatically from one side of the blade edge to the other during stropping so 25 that the strop may have free access to both sides of the edge.

A further object is to provide a clip which is mountable on the blade and is adapted for supporting the guard and tending constantly to retain the guard in its normal position 30 relatively to the blade.

These, and other objects, will be fully described with reference to the accompanying drawings illustrating one example of 35 construction, in which drawings:—

Figure 1 is a longitudinal sectional elevation of an improved stropping device with a safety razor locked therein in position for stropping, the device being assumed to be 40 in movement along the strop in the direction of the arrow.

Figure 2 is a plan of Figure 1 but with the strop indicated by chain lines only.

Figure 3 is an elevation as seen from the 45 left hand end of Figure 1 and with the strop omitted.

Figure 4 is a fragmentary view and similar to Figure 1, but showing the cradle rocked to a reverse position for stropping 50 the other side of the edge of the blade when

the device is in movement along the strop in the direction of the arrow which is the reverse of that in Figure 1.

Figure 5 is similar to Figure 4 but it shows the cradle in a locked condition and 55 the razor only partially inserted.

Figure 6 is a transverse section on the line VI—VI of Figure 4.

Figure 7 is a perspective view of the blade end of the safety razor with the handle broken 60 off.

Figure 8 is a cross section on the line VIII—VIII of Figure 7.

Figure 9 is an end elevation of the razor 65 device in Figure 7.

Figure 10 is a plan view of the razor device in Figure 7.

The carriage or holder is a channel member comprising a base 1 and side walls 2 and 3. Within the channel is a swingable cradle 70 comprising side plates 4 and 5, three rollers 6, 7 and 8 in triangular or staggered disposition being rotatably mounted on spindles 9, 10 and 11 fixed by their ends in the plates 4 and 5. The cradle is suspended from pivots 75 12 and 13 on the walls 2 and 3. The rollers 7 and 8 are provided with flanges 70 and 80 respectively. A strop 14 is passed along the channel and trained about the rollers to form a bight into which the edge of the razor blade 80 is to project. A hollow bead or bridge member 15 extends across the channel near the rear end, and is formed in the middle with a slot to receive a neck 17 formed on the razor handle 19 just within a terminal knob or 85 enlargement 18 which can be seated in the hollow bead 15.

The forward end of the handle 19 is shown 90 screw threaded at 20 for screwing into the thick portion of a blade 22 which may be of the hollow ground type but the handle may be riveted to the blade. Between the screw thread 20 and the plain portion of the handle 19, there is formed a collar or enlargement 23. Before screwing the handle into the blade 22, a clip device 21 is applied to the blade. The screw threaded end 20 is passed through a perforation in the clip and screwed into the blade 22, and when tightly screwed home 95 the collar 23 clamps the clip 21 between itself 100

and the blade 22. As will be seen particularly from Figures 7 to 10, the clip device 21 is of sheet metal, the top part being flanged to fit and seat on the top of the blade and the lower part being shaped to form spring arms 24 and 25 extending to respective sides of the blade 22. The arms 24, 25 are formed at their ends with tangs or pips 26 and 27 projecting at right angles from the arms and these are 10 for supporting the blade guard 28.

As seen in the drawings, the guard 28 is a U-shaped loop or bail having internal dimensions sufficiently large to enable it to swing past the edge of the blade from the position 15 Figure 1 to the position Figure 4. The upper portions of the limbs of this guard are widened at 29 and 30, Figure 7, to overlap the sides of the blade 22, and such widened portions are provided with perforations to enable the tangs or pips 26, 27 to pass through. The upper portions of the limbs are bent out of the plane of the loop 28, so that when such upper portions are more or less flat against the blade 22, the loop portion is inclined away 20 from the blade as seen in Figures 1, 5, 8 and 9. In assembling the parts, the clip 21 is engaged with the guard 28 by inserting the tangs or pips 26, 27 into the perforations of the widened portions 29, 30 and is then applied to the 25 blade 22, the handle 19 being finally screwed into the blade to clamp the clip 21 as above described. The clip 21 having been secured in position with accuracy owing to the disposition of its perforations on the screw 20 30 and to the seating of its flange on the top of the blade, it follows that the tangs or pips 26, 27 will suspend the guard 28 so that its bottom transverse member is correctly disposed beneath the edge of the blade and the lower 35 portions of its side limbs are clear of the blade. Moreover, the pressure of the spring arms 24, 25 against the upper portions 29, 30 of the limbs keeps such portions flat against the blade 22 so that the loop portion of the 40 guard is correctly disposed in relation to the edge of the blade for affording the safety razor characteristics. It is to be noted from Figures 8 and 9 that the tangs or pips 26, 27 normally extend a little over respective ends 45 of the blade. The above described position of the parts, seen in Figures 8 and 9, is the normal position of the parts during a shaving 50 operation.

The top flange of the clip 21 is formed with 55 end extensions 31 and 32 which project beyond the ends of the blade 22, as seen clearly in Figure 10, and these extensions are designed to come to rest and seat upon the inner end portions of the cradle pivots 12 and 13 60 as shown in Figure 6, when the razor is properly inserted into the channel carriage or holder. Such insertion is accomplished by holding the razor in a somewhat erect position, introducing the knob 18 into the seating 65 15 and the neck 17 into the slot 16, and then

lowering the razor as about a pivot until the extensions 31 and 32 come to rest upon the inner ends of the pivots 12 and 13. When the end of the handle 19 has been engaged in the seating 15 and slot 16 as described, no appreciable movement of the razor endwise of the carriage or holder is possible. Consequently, with appropriate dimensions for the parts, the extensions 31 and 32 are bound to seat themselves accurately on the pins 12 and 13. 70 75

It is advisable to lock the razor in the seated position in the holder and for this purpose a pivoted loop or bail-form of catch 33 is adopted. The catch is mounted on pivot pins 34 and 35 on the side walls 2 and 3, and 80 its transverse or arch member is provided with spring fingers 40, 41 which press on the top flange of the clip 21 on the blade when the catch is moved about its pivots to the blade-locking position seen in Figures 1 and 4. The 85 side limbs of the catch 33 are notched at 36 and 37, so that when the catch 33 is moved about its pivots to a reverse position in which it unlocks the razor, the said notches engage with pins or projections 38, 39 on the cradle 90 and lock the latter in a non-swingable position as seen in Figure 5. Naturally, the cradle must be brought to the appropriate intermediate position for this latter locking to 95 be effected.

In operation, the cradle is locked by the catch 33 as just described. The knob 18 on the razor handle 19 is then engaged with the seating 15 and the razor is lowered to bring the extensions 31 and 32 on to the pins 12 and 13 as already explained. Figure 5 shows the razor just before it arrives at this position of rest. In view of the dimensions adopted as above explained and further in view of the cradle being locked immovably in the position shown, the edge of the blade 22 is bound to enter the bight in the strop 14 freely and without possibility of damage. The catch 33 is now moved about its pivots to the position seen in Figures 1, 4 and 6 so as to prevent the extensions 31, 32 from rising from their seating on the pins 12 and 13. As the top bent over portion of the bead 15 prevents the knob 18 from rising and as endwise movement of the razor is prevented by the engagement of the neck 17 in the slot 16, it will be seen that the razor is fixedly held on a three point support in very accurate disposition in relation to the stropping bight. The razor is conveniently stored in this condition in the holder 115 when not in use. 120

When the razor is to be stropped, and assuming it to have been inserted and locked in the carriage or holder as above described, one end of the strop 14 is hooked on to a fixed object, the other end is held to pull the strop taut, and the carriage or holder is reciprocated along the strop. Assume the first stroke imparted to the carriage or holder to be in the direction of the arrow Figure 1, the pull of 125 130

the strop will cause the cradle to rock rightwardly to the position shown, so that the left hand side of the edge of the blade is engaged and rubbed by that portion of the strop at the top left hand portion of the bight. The favourable angle at which the strop impinges against the edge is to be noted. During this stroke of the carriage, the guard 28 retains its normal position in relation to the blade 22, the reason being that the left hand side of the edge of the blade is normally exposed and is free to be wiped or rubbed by the strop. When this stroke of the carriage is finished, the movement is reversed so that the carriage then moves in the direction of the arrow in Figure 4. The reverse pull of the strop causes the cradle to rock leftwardly to the position in Figure 4, so that the top right hand portion of the bight will rub against the right hand side of the edge of the blade. Now, the guard 28 would normally prevent contact of the strop with this side of the edge but owing to the method of supporting the guard 28 the latter is free to be pushed by the flanges 80 of the roller 8 past the blade 22, as shown in Figure 4, so as not to obstruct contact of the strop with the blade. As will be apparent by comparing Figures 1, 4, 8 and 9, the guard 28 when so pushed by the flanges 80 executes a rocking movement about a fulcrum which may be said to be provided by the shoulders at the lower ends of the widened portions 29, 30. During this rocking movement of the guard 28, the tangs or pips 26, 27 remain in engagement and preserve the appropriate disposition of the guard. As the lower or loop portion of the guard moves past the edge of the blade, the upper portions of the limbs move outwards from the thick portion of the blade, thereby stressing the spring arms 24, 25. Thus, when the movement of the carriage is again reversed so that the cradle is returned to the position seen in Figure 1, the spring arms 24, 25, will return the guard 28 to its normal position. The amplitude of rocking movement of the guard 28 against the resistance of the spring arms 24, 25 is relatively small so that in no circumstances is it possible, by reasonable effort, to shift the guard to such an extent as dangerously to expose the edge of the blade. Thus, during shaving, for example, it is quite impossible for the guard 28 to rock or tilt to an unsafe position.

The construction described is capable of various modifications and refinements without departing from the invention as herein-after claimed.

I claim:—

1. A safety razor adapted for insertion into a reciprocatory stropping device of the kind described, said razor comprising a blade, a handle fixed to said blade for interlocking with a support, a clip clamped to said blade by said handle and having projections extending laterally beyond the ends of the

blade and resilient laterally extending arms, a safety guard fulcrumed on one face of said blade and normally held in safety position to one side of the blade by the engagement of said arms, said guard being rockable on its fulcrum to the opposite side of the blade.

2. A safety razor adapted for insertion into a reciprocatory stropping device of the kind described, said razor comprising a blade, a handle fixed into said blade for interlocking with a support, a clip engaging the blade comprising lateral projections forming supports and having laterally extending resilient arms, and a safety guard having a fulcrum formation rockable against the blade and being normally held in safety position to one side of the edge of the blade by the engagement of the resilient arms and rockable on its fulcrum to the opposite side of said edge against the action of said arms.

3. A safety razor adapted for insertion into a reciprocatory stropping device of the kind described, said razor comprising a handle, a blade fixable to said handle, a clip adapted to be clamped between the handle and blade, a guard rockable upon one face of said blade, and elastic means on said clip for supporting said guard on the blade in safety position.

4. A safety razor device adapted for insertion into a reciprocatory stropping device of the kind described, said razor comprising a handle, a blade fixable to said handle, a clip comprising spring arms and adapted for being clamped between handle and blade, a U-shaped guard supported by the clip and pressed against said blade by the spring arms, said guard being rockable on said blade in such manner that the guard loop can swing past the edge of the blade, said spring arms constantly resisting rocking of said guard in one direction.

5. A safety razor device comprising a blade, a handle fixed into said blade and formed with a terminal projection, a blade clip projecting laterally beyond each end of the blade, a guard extending down the ends and beneath the edge of the blade and rockable on the blade from one side of the blade edge to the other and flexible arms on said clip positively engaged with said guard for supporting the same, said arms constantly influencing said guard towards one side of said blade.

6. A safety razor device comprising a handle formed with a terminal projection, a blade fixable to said handle, a blade clip clamped by said handle to said blade and comprising spring arms and a flange extending over the back of the blade and beyond each end of the latter, projections on the ends of the said arms, and a rockable guard comprising perforated limbs with which said projections engage, said arms pressing said limbs against the blade.

7. A safety razor comprising a razor blade, a handle fixed directly into the blade, a clip clamped to the blade by the handle, spring arms on said clip, a guard rockable against the blade and capable of swinging to and from past the edge thereof, said guard being supported by said clip and constantly pressed towards normal position by the spring arms, and projecting devices on said clip and handle for supporting the razor.

8. A safety razor comprising a hollow ground blade, a blade guard comprising arms rockable against one face of the blade, a clip applied to the thick top of said blade, a handle fixed to said blade and clamping said clip thereon, and flexible arms on said clip and having ends for engagement with the rockable guard.

9. A safety razor comprising a hollow ground blade, a handle screwed at one end into a surface of said blade and provided at the other end with locating means adapted for engaging a support, a clip seated on the back of said blade and secured by the screwing in of said handle, and a spring biased blade guard supported by the clip so as to be swingable past the edge of the blade.
